UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

PRESSING MACHINE

Application filed January 23, 1929. Serial No. 334,493.

This invention relates to pressing machines as garment and laundry pressing machines, and has for its object a particularly simple and efficient arrangement of the co-operating pressing elements, by which heavy pressure is applied by the lower pressing element, and a fluid, as steam or air, or both, is blown through the lower pressing element and the work, and also through the padding on the lower pressing element. Preferably air is blown to remove the moisture from the padding or the work during the pressing operation and also, if desired, for drying the padding when the machine is open.

15 The invention consists in the novel features and in the combinations and constructions hereinafter set forth and claimed.

In describing this invention, reference is had to the accompanying drawings in which 20 like characters designate corresponding parts in all the views.

Figure 1 is a side elevation of a pressing machine, embodying my invention, as a power operated machine.

25 Figure 2 is an enlarged sectional view through the buck or lower pressing element.

Figure 3 is a partly diagrammatic view illustrating the manually operated valves, these being shown partly in section.

30 Figure 4 is a plan view of the buck.

Figures 5 and 6 are views similar to Figures 1 and 3 illustrating the invention embodied as a foot operated machine.

I have here shown my invention as applied to the conventional type of pressing machine including a buck 1, a head 2 movable toward and from the buck, the buck having an upwardly movable top or pressing wall which is foraminous or perforated, and 40 means for applying internal pressure to the buck to move said wall upwardly and to blow air through the top wall, the padding overlying the buck, and the garment or other article being pressed.

45 The blowing of air or other fluid relieves or softens the initial shock of the head coming on the work. The work is pressed against the head so that at first pressure is very light or the work is merely touching against the head, while the air or other fluid

is passing through the previous upper wall of the expansible chamber and through the padding and work. Thereafter, the pressure increases when the work is pressed against the head, or the head against the work, with sufficient force to retard the passage of the fluid through the previous top wall. This operation is particularly advantageous when operating upon certain classes of goods as it avoids a sudden bringing down or slamming of the head on the work with a sudden pressure.

The buck 1 includes a base 3 mounted on a suitable bracket or goose neck 4, which in turn is mounted upon a table 5 supported by framing 6 of any suitable construction. The head 2 is carried by the conventional lever or yoke 7 pivoted between its ends at 8 to a standard 9 rising from the frame.

The head may be actuated by any suitable mechanism either by foot or power, and as here shown, the mechanism for actuating the head in addition to the lever 7 includes toggle links 10 and 11 pivoted at 12 and 13 to the rear arm of the yoke lever and to the base of the frame respectively and pivoted together at 14. The link 11 has a forwardly extending arm 15 to which power is applied.

In Figures 1 and 3, the power is applied to the arm 15 by a cylinder 16 having the rod 17 of its piston pivoted at 18 to the forward end of the arm 15. The piston is single acting and oscillating. When the press is closed and the pressure applied to the internal chamber of the buck, as will be presently described, the press is held closed by the fact that the toggle links 10, 11 are in a dead center line or slightly beyond the dead center line. The head is opened, when the forces tending to hold it closed are released, by springs 19 and 20. In Figures 5 and 6, the forwardly extending arm 15 is shown as formed with a pedal plate 21 by means of which the head is brought down onto the buck.

The buck 1, in addition to the base comprises an extensible and compressible chamber 23, the top wall of which moves upwardly and downwardly against the head to apply heavy pressure, this chamber having a

foraminous top wall 24. The chamber is formed with upright flexible side walls 25 having inwardly turned margins 26 at their upper ends which lap the margin of the per-
5 forated metal plate 27. The walls of the chamber are overlaid with a suitable fibrous padding 28 which is held in position by a band 29 enclosing the lower margin of the padding and the base of the buck, this band
10 being clamped or tightened on the padding in any suitable manner. Preferably, a number of compression springs 30 are located in the chamber which thrust at their lower ends against the base or a plate 31
15 overlying the base and to which all of the springs are secured at their lower ends, and at their upper ends against the perforated plate 27. The springs normally hold the chamber 23 expanded or extended before the
20 head is brought down on the buck.

In the form shown in Figures 1 and 3, the flow of air under pressure to the cylinder 16 is controlled by manually operable valves comprising a valve casing 32 having a nor-
25 mally closed spring pressed intake valve 33 therein and a normally open exhaust valve 34. An inlet pipe 35 connects to one end of the valve casing and an outlet pipe leading from the casing at a point between the valves
30 and is connected to the head of the cylinder 16. The valves are connected together by a stem 37 so that they act as a unit.

The valves are operated by manual means, as a push button 38, acting on a lever 39 which
35 in turn acts upon another lever 40 which thrusts against the stem 41 of the exhaust valve 34. A spring 42 returns the push button to its normal position when released.

Obviously, depression of the push button
40 38 will permit the air to flow from the inlet pipe 35 to the cylinder 16 to actuate the piston therein and bring the head down against the work on the buck and compress the buck into the position shown in dotted lines, Figure 2.

45 For additional pressure and for blowing air through the work on the buck, manual means is provided for controlling the flow of compressed air to the chamber 23. This means comprises a valve casing 43 having a normally closed spring pressed intake valve
50 44 therein and a normally open exhaust valve 45, these valves being operated by a push button 46 and levers 47 and 48 similar to the push button 38 and levers 39 and 40 with the exception that the lever 48 is a two arm lever. The valve casing 43 is connected at one end to a feed pipe 49, and is connected at a point between the valves to an inlet passage 50 in the buck by a pipe 51.

60 In order to hold the valves 44 and 45 in their operated position, pressure operated means is provided consisting of a diaphragm chamber 52 having a diaphragm 53 therein acting upon a sliding stem 54 which in turn
65 acts on the lever 48. The pressure side of

the diaphragm chamber is connected by a duct 55 to the interior of the valve casing between the valves 44 and 45.

Obviously, upon depression of the push button 46, air will flow from the feed pipe 49 through the valve casing 43 and pipe 51 to the pressure chamber 23 of the buck, and when the valves are so operated, air will also pass through the duct 55 to the diaphragm chamber 52 actuating the diaphragm 53 therein to hold the lever 48 in its operated position.

To release the pressure in the chamber 23, means is provided for exhausting the air from the pressure side of the diaphragm chamber 52, this means consisting of a valve casing 56 having a normally closed spring pressed exhaust valve 57 therein, the casing being connected by a pipe 58 to the pressure side of the diaphragm chamber 52. The exhaust valve 57 is operated by a release lever 59 grouped with the push button 46.

In operation, the operator after laying the work on the buck, depresses the push button 38 permitting air to flow to the cylinder 16 and actuate the piston therein and while holding down the push button 38 depresses the push button 46 to permit air to enter the pressure chamber 23. When the pressure is applied to the chamber 23, the operator may release both push buttons and the press will be held closed by reason of the force applied to the head from the expanded buck against the straightened toggle, although as soon as the operator releases the push button 38 the air is free to exhaust from the cylinder 16, back through the pipe to the valve casing 32 and out through the passage controlled by the exhaust valve 34. While the garment or other article is being pressed, air is blown through the padding and the garment, to dry it, from the internal chamber 23.

To open the press, the release lever 59 is operated and as soon as the upward pressure of the chamber 23 is released, and hence the thrust on the toggle relieved, the springs 19 and 20 react to open the press.

When the press is opened, the push button 46 may be depressed to cause air to blow through the buck and dry the padding.

In the form shown in Figures 5 and 6, the operator depresses the pedal 21 to close the press and holds his foot on the pedal 21 until the lower buck is under air pressure.

In Figure 6, a two hand control is provided for controlling the flow of air to the pressure chamber in the lower buck, and the valves are of the same construction as those shown in Figure 2, with the exception that both valves are provided with diaphragm chambers and diaphragms therein corresponding to diaphragm chamber 52 and diaphragm 53.

In Figure 6, both push buttons must be depressed. Depression of the push buttons 60

and 61 opens the intake valves 62 and 63 in the valve casings 64 and 65 respectively and closes the exhaust valves 66 and 67 so that the air passes from the feed line 68 through the valve casing 65, thence through pipe 69 to the valve casing 64, thence through pipe 70 to the internal chamber of the buck. Air passes from valve casing 64, through duct 71, to diaphragm chamber 72 and locks the valves operated by the push button 60 in their operated positions, and also passes from the diaphragm chamber 72, through pipes 73 and 74, to the diaphragm chamber 75 of a valve mechanism operated by the push button 61.

15 To open the press, the release lever 76 is operated to open the exhaust valve 77, the casing 78 of which is connected by a pipe 79 to the pipes 74 and 73.

Obviously, both bush buttons 60 and 61 must be operated since if the button 60 only is operated, no air will flow from the feed pipe, and if the button 61 only is operated the air will pass from the valve casing 63 through pipe 69 to valve casing 64 and out through the port controlled by the exhaust valve 66.

In either form of my invention, the pressure is applied by first bringing the head down on the buck and compressing the compressible chamber against the springs in the chamber. Pressure is applied by internal pressure in the buck, and while pressure is being applied to the buck, the air is blowing out through the foraminous top of the pressure chamber of the buck through the padding and the work thereon. The air may be blown through the work on the buck when the head is open by depressing the push button 46 in Fig. 3, or push buttons 60 and 61 40 in Fig. 6.

What I claim is:

1. A pressing machine including a buck having a compressible chamber, a head movable into cooperative relation with the buck 45 to compress the same, means for actuating the head, manual means for controlling the flow of a fluid to said chamber to expand the same against the head, and springs in said chamber for resisting compression thereof.

50 2. A pressing machine including a buck having a compressible chamber having a pervious top wall, a head movable into cooperative relation with the buck to compress the same, means for actuating the head, manual means for controlling the flow of a fluid to said chamber to expand the same against the head, and springs in said chamber for resisting compression thereof.

In testimony whereof, I have hereunto signed my name, at Syracuse, in the county of Onondaga, and in the State of New York, this 12th day of January, 1929.

ERNEST DAVIS.
